UNITED STATES PATENT OFFICE.

WINGATE THOMAS, OF CHICAGO, ILLINOIS, ASSIGNOR, BY MESNE ASSIGNMENTS, TO
PORCELAIN TILE COMPANY, OF CHICAGO, ILLINOIS, A CORPORATION OF ILLINOIS.

ENAMELED SHEET-METAL TILE.

Application filed October 6, 1926. Serial No. 139,806.

This invention relates to the art disclosed in Patent No. 1,594,614, granted August 3, 1926, to George D. Haines. The Haines patent illustrates and describes a method of 5 constructing tiled walls which includes the application of enameled sheet-metal tiles to a foundation sheet having grooves or the like to receive flanges on the tiles. In practice, the tiles are usually three inches wide and six 10 inches long, although they may be of any desired dimensions. Preferably, each tile has a marginal flange on all four sides to extend into the locating grooves in the foundation sheet. The outer face of the tile, including 15 its flanges, is coated with vitreous enamel.

In tiling a surface in accordance with the Haines patent, it is almost always the case that the length of the wall, ceiling or other surface is not an exact multiple of the length 20 of the tile, making allowance for the cement-filled joints between the tile. Moreover, the tiles are usually set to break joints. It is therefore necessary to provide fractional tiles to fill the required space, such fractional tiles 25 varying in length from one-eighth inch up. For various reasons it is impracticable to provide machinery or implements whereby tiles may be satisfactorily cut "on the job" to the required length. Indeed, the cutting of 30 enameled sheet-metal tiles, even at the factory, is difficult of satisfactory performance, inasmuch as the enamel is apt to shatter for some distance from the line of severance, and the material being cut soon dulls or destroys 35 the cutting element.

While fractional-length tiles can be made by methods heretofore used, the cost of stamping out and enameling a small tile is practically the same as for a full-size tile, and tiles 40 of very short length are troublesome to handle in the manufacturing operations.

The object of the present invention is to solve the difficulties above referred to. This object has been attained by making fractional-length tiles in connected sets, as will 45 appear more fully from the following description.

In the accompanying drawings—

Figure 1 is a face or plan view of a connected series or set of fractional-length tiles constructed in accordance with my invention.

Fig. 2 is a side edge view of a series of fractional-length tiles shown in Fig. 1

Fig. 3 is a transverse sectional view on an enlarged scale. 55

Fig. 4 is a view similar to Fig. 1, but showing tiles of a different length from those illustrated in Fig. 1.

Fig. 5 is a perspective view of a fractional-length tile after separation from a series of 60 such tiles.

The invention contemplates the production of connected sets of vitreous-enamelled sheet-metal tiles of less than full length. Preferably, the length of the fractional-length tiles 65 will be multiples of one-eighth of an inch up to about three inches in length. Fig. 1 illustrates a connected set or series of fractional-length tiles 1, each having at its ends rearwardly extending flanges 2 to enter the 70 tile-locating grooves of the foundation sheet. The outer face of the tile, including its flanges, is coated with vitreous enamel, the inner side of the tile preferably also being 75 enamelled. The flanges 2 of the series of fractional-length tiles shown in Fig. 1 are connected together by narrow webs 2^a. As shown in Fig. 2, these webs are of less width than the flanges.

A connected series of fractional-length 80 tiles constructed in accordance with my invention may be of any convenient length, and the number of fractional-length tiles in each set will vary with the length of each tile and other practical considerations. Fig. 4 illustrates a connected set of two fractional-length tiles 1^a, said tiles being connected together by narrow webs, such as 2^a. 85

A connected series of fractional-length tiles, such as hereinbefore described, may be 90 manufactured very cheaply. In a steel sheet or strip of the proper width a series of transverse slots 3 are punched, the ends of the slots extending relatively close to the edges of the strip. The side or long edges of the strip 95 are then bent to form flanges 2 which are perpendicular to the plane of the strip, the line along which bending occurs intersecting the slots 3 so that the webs 2^a at the ends of the slots are narrower than the flanges. The 100 connected series of fractional-length tiles thus produced is then enamelled (as indicated in Fig. 3), the cost of enameling a connected series of fractional-length tiles being approximately the same as would be the cost of 105 enameling a single independent fractional-

length tile. Inasmuch as the tiles are spaced apart from each other, the long or side edges of the tiles become coated with enamel, there being in consequence no raw or unfinished edges.

In practice, the tile setter is supplied with a quantity of connected sets of fractional-length tiles of different lengths. When a fractional-length tile is needed, the tile setter 10 selects a set of tiles of the required length and either breaks a tile from the set or cuts off the tile by means of a tin snip. The webs 2^a, while of sufficient strength and rigidity to hold the tiles together during the various 15 manufacturing operations and in transportation, are so narrow as to be easily severed by bending or shearing. The webs 2^a being narrower than the flanges 2, any projection 2^x (Fig. 5) remaining from the cutting or break- 20 ing operation is at a distance from the face of the tile and becomes embedded in the cement-filled joint, and hence does not mar the appearance of the finished job.

Inasmuch as the vertically extending 25 grooves of the foundation sheet extend at regular distances from each other and are arranged to break joints, there will not be a continuous vertical groove at each end of the

space to be tiled; consequently the fractional-length tiles herein disclosed have no flanges 30 at their long sides, the flanges 2 being provided only at the ends of said tiles to fit with in the horizontal grooves of the foundation sheet.

It will be seen that the invention herein 35 disclosed obviates the expense and difficulties involved in manufacturing separate fractional-length tiles and in cutting full-length tiles to produce the required fractional 40 lengths.

I claim as my invention:

1. A connected set of fractional-length flanged enameled sheet-metal tiles, said set comprising a plurality of fractional-length tiles, and webs connecting the flanges of said 45 tiles, said webs being narrower than the flanges.

2. A connected set of fractional-length flanged enameled sheet-metal tiles, said set comprising a plurality of fractional-length tiles, each tile being flanged at two opposite 50 edges, and the tiles being united only at said flanged edges.

In testimony whereof, I have hereunto affixed my signature.

WINGATE THOMAS.
